UNITED STATES PATENT OFFICE.

LAROY C. MONISMITH, OF GLENVIL, NEBRASKA.

SPARK-PLUG.

1,305,924.

Specification of Letters Patent. Patented June 3, 1919.

Application filed September 13, 1918. Serial No. 254,024.

To all whom it may concern:

Be it known that I, LAROY C. MONISMITH, a citizen of the United States, residing at Glenvil, in the county of Clay and State of Nebraska, have invented new and useful Improvements in Spark-Plugs, of which the following is a specification.

This invention relates to spark plugs, for ignition purposes in internal combustion engines, and has for its object the provision of a spark plug having a porcelain insulating portion molded within the shell of the plug and about internal projections on the shell whereby the porcelain portion will be a permanent part of and be inseparable from the shell to prevent any possible displacement, the porcelain, being also molded about the central contact wire which is furthermore provided with a retaining flange.

A very important object is the provision of a spark plug of this character in which the firing points are disposed at a considerable distance beyond the end of the plug and spaced an unusually long distance apart whereby a very long hot spark may be produced, longer than in the commonly used plugs, to insure explosion of a charge, the thickness and special construction of the porcelain core preventing short circuiting within the plug even though the firing points become fouled.

Another object is the provision of a spark plug of this character which will be extremely simple and inexpensive in manufacture, efficient and durable in use, and a general improvement in the art.

With the above and other objects and advantages in view, the invention consists in the details of construction to be hereinafter more fully described and claimed, and illustrated in the accompanying drawings in which:—

Figure 1 is a side elevation of a plug constructed in accordance with my invention, Fig. 2 is a longitudinal sectional view therethrough and

Fig. 3 is a cross sectional view.

Referring more particularly to the drawing the numeral 5 designates the shell or body portion of the plug which is formed angular in cross section as shown and which has one end reduced and externally threaded for engagement within the usual opening in an engine cylinder, as shown at 6. Extending inwardly from the inner wall of the body portion 5 are projections 7 adapted to

serve as retaining means for the porcelain core 8 which is molded directly within the body 6 and which has both ends extending beyond the ends of the body 5 as shown at 9 and 10. The projecting end 10 is formed convex as shown.

Disposed centrally of and molded within the porcelain core 8 is a contact member 11 in the form of a wire which is provided with an outwardly extending circumferential flange 12 which will prevent any displacement of the contact member 11 in respect to the core 8. At its other end, the contact member 11 is threaded as shown at 13 and has threaded thereon a locking nut 14 which bears against the end 9 of the core for holding the contact member 11 firmly in position. It will be noted that the other end of the contact member 11 extends an appreciable distance beyond the convex end 10 of the core so as to extend an appreciable distance into the firing chamber of an engine cylinder.

The other contact member, that is the ground connection member, extends from the threaded end 6 of the shell or body 5 and is designated by the numeral 15. At its extremity the contact member 15 is provided with a laterally offset portion 16 directed toward and in alignment with the end of the contact member 11. The distance between the end of the laterally offset portion 16 of the contact member 15 and the contact member 11 is several times the distance between the contact points of the ordinary form of spark plug whereby an extremely long hot spark may be obtained. Owing to the peculiar construction of the plug which is so formed that the central contact member 11 is comparatively remote from the outer shell 5, there will be practically no danger of short circuiting within the core even though the contact members 11 and 16 should become fouled. Furthermore, in view of the fact that the core is molded directly into the shell, there will be no space between the core and the shell for the accumulation of soot, which would result in fouling of the plug and resultant short circuiting with the core.

From the foregoing description and a study of the drawing it will be apparent that I have thus provided a very simply constructed spark plug by means of which an unusually long and hot spark may be produced and in which the danger of short cir-

cuiting within the body of the plug will be reduced to the minimum.

Having thus described my invention I claim:—

5 A spark plug comprising an outer shell provided at one end with a threaded portion, a plurality of spaced inwardly extending projections formed on the inner periphery of said shell and arranged in circumferential series, an insulating core of porcelain molded within said body and engaging the entire internal periphery thereof and having both ends extending beyond the ends of the body, the end projecting beyond the threaded end of said shell being a section of a

sphere, a contact member extending centrally of and embedded within said core and having its active end extending an appreciable distance beyond the partially spherical end of said core, a retaining flange 20 formed on said central contact member intermediate its ends whereby longitudinal displacement thereof will be prevented, and a contact member extending from said shell and having a laterally directed end extending toward the side of said first named contact member adjacent its end. 25

In testimony whereof I affix my signature.

LAROY C. MONISMITH.
